STEAM BOILER

Paul Pothier and Edmond Vigneault, Trois-Rivières, Quebec, Canada

Application December 21, 1935, Serial No. 55,601

3 Claims. (Cl. 122—467)

The present invention pertains to a novel steam boiler designed preferably, but not necessarily, for use in connection with an oil burner. The principal object of the invention is to provide a simple and efficient device of this character having large water heating surfaces and a construction for super-heating the steam. Other features of the invention include a booster line for pressure feed of fuel to an oil burner and a water guard for preventing the entrance of water into the steam drawn off from the boiler.

The boiler includes a shell in which is formed a water tight chamber for conducting hot gases from an oil burner or other source of heat. Steam is collected in a system above the water level and is returned downwardly into the chamber for super-heating. It is withdrawn from a lower point in the chamber to the outlet pipe leading to radiators or other points of use. This delivery pipe receives the final gas exhaust pipe so that the heat in the exhaust gas may also be utilized.

Other objects and features of the invention will appear as the description proceeds.

The invention is fully disclosed by way of example in the following description and in the accompanying drawing in which

Figure 1 is a vertical section of the device;

Figure 2 is a plan section taken at the lower part of the boiler, and

Figure 3 is a plan section taken at the upper part of the boiler.

Reference to these views will now be made by use of like characters which are employed to designate the corresponding parts throughout.

In Figure 1 the numeral 1 designates the shell of the boiler having an opening 2 in its bottom and its top covered by a dome 3 after the inner assembly has been completed. The opening 2 is designed to accommodate an oil burner of any suitable construction for the purpose of generating steam within the apparatus as will presently be described.

A hollow core or drum 4 rests on a ring 5 in the bottom of the shell 1. A conical chamber member 6 is secured to a neck 7 at the top of the drum 4. The member 6 is covered by an annular plate 8 to which is secured an upwardly extending tube 9 for a purpose that will presently be described. Further, a tube 10 is secured to the member 6 over the neck 7 and extends concentrically into the tube 9 as clearly illustrated in Figure 1. The hot gases generated by the burner at the opening 2 rise in the drum 4 and inner tube 10.

Vent plugs 11 and 12 are mounted the first in

the dome 3 and the second on tube 9 are controlled by cables 12' and 13 passing over suitably positioned pulleys 14 and 15. The plugs or traps are opened only for the purpose of permitting the cold air in the apparatus to escape during starting, and are immediately closed when heat is generated. Thereafter, the hot gases pass from tube 10 downwardly through tube 9 to the chamber 6, the top of tube 9 being closed by plate 12.

Vertical fire tubes 16 are mounted in the plate 8 and in another horizontal plate 17 supported near the base of the dome 3. The hot gases rise from chamber 6 through the fire tubes and into the dome 3 from which they escape through a pipe 18.

Cold water is admitted to the water space in the boiler through a pipe 18' entering the dome 3 and there formed as a spiral 19, the lower end of the spiral being continued as a pipe line 20 entering the shell 1 and extending to the bottom thereof as indicated by the numeral 21. Thus, the entering cold water is heated at substantially the point of entry or very near thereto.

The steam generated in the boiler is collected in a horizontal ring-shaped pipe 22 surrounding the fire tubes 16 above the water level and formed with openings 23 for the admission of steam thereto. A separating plate 24 extending beneath the tube 22 prevents entry of moisture into the openings 23.

From the pipe 22 the dry steam enters another spiral 25 in the dome 3 and flows downwardly in a coil 26 in the tube 9. The steam is then carried upward in a pipe 27 leading from the bottom of the coil to an external line 28 communicating with the final outlet pipe 29 enclosing the exhaust pipe 18 to heat the steam further from the exhaust. The steam, as it flows through the coil 26, is superheated.

A line 30 of comparatively small diameter is tapped into the spiral 25 and carried into the inner tube 10 where it is formed as a coil 31 and is then continued into the drum 4 in the form of a wider coil 32. From the lower end of the coil, the line is continued as at 33 to the supply side of the oil burner (not shown) to force the fuel mixture through the burner under pressure.

This extension 33 may be connected to the fuel tank or to any other desired point in the fuel supply line.

Water tubes 34 are mounted in the top and bottom of the drum 4 to increase the circulation of water through the hot gases in the drum. A

safety valve 35 is preferably mounted in the steam line 28.

Although a specific embodiment of the invention has been illustrated and described, it will be understood that various alterations in the details of construction may be made without departing from the scope of the invention, as indicated by the appended claims.

What we claim is:—

- 10 1. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube said chamber member having its bottom joined to the lower part of the first-named tube and the upper part of said drum.
- 15 2. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube said chamber member having its bottom joined to the lower part of the first-named tube and the upper part of said drum.
- 20 3. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube, a steam collector pipe beneath said plate, a coil extending from said pipe into the space between said tubes, and an outlet pipe extending from the lower end of said coil, and a booster pipe extending from said collector pipe and coiled in the first-named tube and in said drum said chamber member having its bottom joined to the lower part of the first-named tube and the upper part of said drum.
- 25 4. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube, a steam collector pipe beneath said plate, a coil extending from said pipe into the space between said tubes, and an outlet pipe extending from the lower end of said coil, and a booster pipe extending from said collector pipe and coiled in the first-named tube and in said drum said chamber member having its bottom joined to the lower part of the first-named tube and the upper part of said drum.
- 30 5. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube, a steam collector pipe beneath said plate, a coil extending from said pipe into the space between said tubes, and an outlet pipe extending from the lower end of said coil, and a booster pipe extending from said collector pipe and coiled in the first-named tube and in said drum said chamber member having its bottom joined to the lower part of the first-named tube and the upper part of said drum.
- 35 6. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube, a steam collector pipe beneath said plate, a coil extending from said pipe into the space between said tubes, and an outlet pipe extending from the lower end of said coil, and a booster pipe extending from said collector pipe and coiled in the first-named tube and in said drum said chamber member having its bottom joined to the lower part of the first-named tube and the upper part of said drum.

mainder of the first-named tube in spaced relation thereto, a plate surrounding the top of the second tube, tubes extending from the top of said chamber member through said plate, and means for closing the upper end of the second tube, a steam collector pipe beneath said plate, a coil extending from said pipe into the space between said tubes, and an outlet pipe extending from the lower end of said coil said chamber member having its bottom joined to the lower part of the first-named tube and the upper part of said drum.

3. In a boiler, a shell, a water-sealed drum in said shell and having a gas inlet in its bottom, water tubes passing through the top and bottom of said drum, a tube extending vertically from the top of said drum and in communication therewith, a chamber member enclosing the lower part of said tube and having its top formed with an opening around said tube, another tube secured in said opening and enclosing the remainder of the first-named tube in spaced relation thereto, a plate surrounding the top of the second tube, tubes extending from the top of said chamber member through said plate, and means for closing the upper end of the second tube, a steam collector pipe beneath said plate, a coil extending from said pipe into the space between said tubes, and an outlet pipe extending from the lower end of said coil, and a booster pipe extending from said collector pipe and coiled in the first-named tube and in said drum said chamber member having its bottom joined to the lower part of the first-named tube and the upper part of said drum.
